DESIGN FOR A SCREW DRIVER BIT

Edwin A. Bakeman, Belding, Mich., assignor of
one-half to John H. Van Camp, Belding, Mich.

Application February 7, 1941, Serial No. 98,835

Term of patent 14 years

To all whom it may concern:

Be it known that I, Edwin A. Bakeman, a citizen of the United States, residing at Belding, in the county of Ionia and State of Michigan, have invented a new, original, and ornamental Design for a Screw Driver Bit, of which the following is a specification, reference being had to the accompanying drawing, forming part thereof.

Figure 1 is a side elevational view of a screw driver bit showing my new design.

Figure 2 is a side elevational view taken at right angles to Figure 1.

Figure 3 is a top plan view, and
Figure 4 is a bottom plan view.

I claim:

The ornamental design for a screw driver bit, as shown.

EDWIN A. BAKEMAN.
